US00D917753S

(12) **United States Design Patent** (10) **Patent No.:** **US D917,753 S**
Guo et al. (45) **Date of Patent:** **** Apr. 27, 2021**

(54) **COMBINED LED PEN LIGHT WITH LASER
POINTER**

(71) Applicant: **AEC LIGHTING SOLUTIONS CO.,
Ltd, Shanghai (CN)**

(72) Inventors: **Shujian Guo, Shanghai (CN); Xun
Zhang, Shanghai (CN)**

(73) Assignee: **AEC LIGHTING SOLUTIONS CO.,
LTD, Shanghai (CN)**

(**) Term: **15 Years**

(21) Appl. No.: **29/692,371**

(22) Filed: **May 24, 2019**

(30) **Foreign Application Priority Data**

Nov. 29, 2018 (CN) 201830684287.3

(57) **CLAIM**

The ornamental design for an combined LED pen light with laser pointer, as shown and described.

DESCRIPTION

FIG. 1 is a perspective view of the combined LED pen light with laser pointer showing my new design;

FIG. 2 is a left side elevation view thereof;

FIG. 3 is a right side elevation view thereof;

FIG. 4 is a rear elevation view thereof;

FIG. 5 is a front elevation view thereof;

FIG. 6 is a top plan view thereof; and,

FIG. 7 is a bottom plan view thereof.

Throughout the drawings the broken lines depict portions of the combined LED pen light with laser pointer that form no part of the claimed design.

1 Claim, 3 Drawing Sheets
